UNITED STATES PATENT OFFICE.

EDGAR SCOFIELD, OF NEW YORK, N. Y., ASSIGNOR TO ANCHOR CAP AND CLOSURE CORPORATION, OF LONG ISLAND CITY, NEW YORK, A CORPORATION OF NEW YORK.

FRICITION CAP FOR BOTTLES AND JARS.

Application filed January 28, 1926. Serial No. 84,276.

The present invention relates broadly to cap and jar closures and more specially to a bottle cap adapted as a dress and user's closure for catsup bottles or the like.

5 Heretofore in the art, in the packaging of catsup, chili sauce and the like, it has been customary to provide a substantially permanent closure for packing and shipping, and also a user's closure as a dress for 10 the package on the shelves of salesrooms and adapted as a temporary closure for use after the permanent seal has been broken and while the contents of the container is being used up. The most common type of cap has 15 been that of the screw thread type although friction caps have been proposed. The difficulty with the friction type of caps heretofore used in the art is due to the fact that such caps quickly become loose in use and 20 therefore are impractical.

The present invention overcomes the difficulties of the known art by providing a friction type of cap constructed in such manner as to be easily applied and removed 25 and wherein many removals and reapplications do not destroy the resilient character of the cap nor seriously impair its gripping qualities. In the preferred form, the friction cap of the present invention is adapted 30 to cooperate with a sealing surface on the container in such manner that the contact between this sealing surface and the cap is a relatively long inclined contact area extending diagonally of the skirt of the cap so 35 that a relatively large portion of the skirt of the cap is available as an elastic area to maintain the required frictional engagement. The cap may be used also on other types of sealing surfaces such as a bulbous finish, 40 taper finish or the like.

It is realized that the invention may be carried out in constructions other than those specifically disclosed in this specification and drawings, and therefore, the disclosure herein 45 with is to be considered as illustrative and not in the limiting sense.

Fig. 1 illustrates the neck of a container showing a cap of the present invention in cross section and illustrating the container 50 as being permanently closed by a closure cap of the crown type, a portion of which cap is shown in section.

Fig. 2 illustrates the preferred form of the cap comprising the present invention.

55 Fig. 3 is a cross section through the neck

of the container and the present cap is taken on line A—A, Fig. 1.

Referring now more especially to the drawings, the preferred form of the present invention comprises a cap having a cover 60 portion 1, having a skirt portion 2. The upper portion of the skirt may be slightly angularly inclined as at 4 and the skirt adjacent the top portion may be knurled to provide a grip for removing the cap. The 65 lower edge of the cap preferably, though not necessarily, may be finished with the well known wire edge 6. The cylindrical portion of the skirt is provided with indentations 7 having an inclined major portion 8 70 and circumferential extending portions 9 and 10. Preferably, these indentations which may be elongated S-shaped locking lugs, are arranged around the cap at substantially diametrically opposite positions as 75 is illustrated in Fig. 3. These indentations are preferably adapted to cooperate with a sealing surface 11 on the mouth of a suitable container 12, and where desired, a substantially permanent closure such as a crown 80 cap 14 may be used to close the mouth of the container; and the cap of the present invention is therefore constructed to fit over such permanent closure.

In the formation of glass articles, such as 85 bottles, defects in the sealing surface are likely to occur on lines parallel to the axis of the mouth of the container. It will be observed that the line of contact between the friction lugs on the cap and the sealing surface on the container is in its major portion 90 an inclined line which curves in such manner that the entire bases of the locking lugs are in contact with the sealing surface 11 on a container. The inclined portion has many 95 advantages, for example, its inclined direction overcomes any difficulties which may be encountered by the way of straight line defects on the finish of the glass; it also permits a tight gripping of the finish by the 100 locking lug because of the fact that a large portion of the skirt of the cap supports the gripping lugs in their function. If the skirt of the cap be cut at right angles to the axis thereof by a plurality of planes, it will be 105 observed that each one of these planes will cut through a contacting portion of the lug with the sealing surface as is shown in the single cross section illustrated in Fig. 3.

The metal in each of these cross sections is 110

effective to maintain the lug, or contacting part at the plane, in contact with the sealing wall, and thus it will be seen that a very effecting sealing force is maintained when 5 the cap is forced over a sealing finish that has a slightly larger diameter than the internal measurement between the contacting faces of the locking lugs.

10 The end portions of the locking lugs present areas which are vertically spaced apart and that circumferentially bear against the sealing surface. The end portions tend to pull the central portion of the lug tightly against the sealing surface. The action of 15 each lug from this consideration, is somewhat like that of pulling a piece of wire bent in the form of a distorted S shape against the sealing surface by pulling on each end of the piece of wire in opposite 20 directions around the bottle neck and thereby pulling the central inclined portion tightly against the sealing surface.

Having described my invention, what I claim is:—

25 1. A closure cap of the friction type comprising a cover portion, a substantially cylindrical skirt depending therefrom, and locking lugs in the skirt of said cap, said lugs having end portions having a substantially circumferential direction and an intermediate inclined portion joining said end portions.

30 2. A closure cap of the friction type comprising a cover portion, a substantially cylindrical skirt depending therefrom, locking lugs in the skirt of said cap, said lugs having end portions having a substantially circumferential direction and an intermediate inclined portion joining said end 35 portions, and a reenforcing edge adjacent the lower portion of said lugs.

35 3. A closure cap of the friction type comprising a cover portion, a cylindrical skirt, and S-shaped locking lugs in the side wall 40 of said skirt.

45 4. A closure cap of the friction type com-

prising a cover portion, a skirt depending therefrom, and S-shaped locking lugs in the side wall of said skirt, and disposed on substantially diametrical sides of said skirt.

50 5. A closure cap of the friction type comprising a cover portion, a skirt depending therefrom, locking lugs in said skirt adjacent the lower portion thereof, said lugs comprising indentations with a rounded 55 bottom portion adapted to form a line contact with a substantially cylindrical sealing surface, said line of contact being of a circumferential direction on the ends and of a helical direction between said ends.

55 6. A deep skirt bottle cap comprising a cover portion, a skirt depending therefrom, and locking lugs in said skirt adjacent the lower portion thereof formed from indentations having an elongated body with end 60 portions extending at an angle thereto adapted to form a line contact with a substantially cylindrical sealing surface, said line of contact extending circumferentially and longitudinally of said skirt.

70 7. A closure cap for bottles comprising a cover portion, a depending skirt, two pairs of diametrically disposed locking lugs formed from indentation inclined at an angle to the cover portion of the cap to 75 form a helical contact with a cylindrical sealing zone with the end portions thereof extending in a substantially circumferential direction.

80 8. A closure cap comprising a cover portion, a depending skirt, locking lugs in said skirt, said lugs having an inclined portion with respect to the cover portion with the upper end thereof extending in a substantially circumferential direction.

85 9. A closure cap comprising a cover portion, a depending skirt, locking lugs in said skirt, said lugs having an inclined portion relative to the cover portion with the lower end thereof extending in a substantially circumferential direction.

EDGAR SCOFIELD.
